A. AND H. INGRAM,
CLOSURE FOR JARS, BOTTLES, AND OTHER RECEPTACLES,
APPLICATION FILED SEPT. 8, 1919. RENEWED JUNE 11, 1920.
1,353,909. Patented Sept. 28, 1920.

UNITED STATES PATENT OFFICE.

ALFRED INGRAM AND HARRY INGRAM, OF BROOKLYN, NEW YORK, ASSIGNEES TO INGRAMS INCORPORATED, OF NEW YORK, N. Y., A CORPORATION OF NEW YORK.

CLOSURE FOR JARS, BOTTLES, AND OTHER RECEPTACLES.

1,353,909.

Specification of Letters Patent. Patented Sept. 28, 1920.

Application filed September 8, 1918, Serial No. 322,403. Renewed June 11, 1920. Serial No. 388,347.

To all whom it may concern:

Be it known that we, ALFRED INGRAM and HARRY INGRAM, citizens of the United States, and residents of Brooklyn, in the county of Kings and State of New York, have invented certain new and useful Improvements in Closures for Jars, Bottles, and other Receptacles, of which the following is a specification.

10 The invention pertains more particularly, although not exclusively, to closures of the screw cap type adapted for sauce and catsup and other receptacles.

We present our invention as embodied in 15 a screw-cap comprising a threaded barrel portion and a non-rotary top portion having a depending central part bearing on its side a gasket, said depending portion and gasket being adapted to be forced in the mouth of 20 the receptacle so that the gasket may seal against the inner upper side walls of said mouth. The gasket preferably comprises a vertical band having a downwardly and inwardly tapered lower edge. The top portion 25 of the closure extends outwardly from said depending portion and is held within the top of the barrel portion by spring fingers cut from said portion, and said barrel portion around its upper edges is bent down- 30 wardly and then flanged inwardly over the peripheral portions of the top member of the closure whereby, when the barrel portion is screwed downwardly upon the neck of the bottle, said inwardly flanged portion 35 thereof firmly engages the upper outer portion of the top and forces the depending member of said top downwardly into the mouth of the bottle with sealing effect.

The invention will be fully understood 40 from the detailed description hereinafter presented, reference being had to the accompanying drawings, in which:

Figure 1 is a central vertical section through a portion of the neck of a bottle 45 with the cap or closure of our invention applied thereto preparatory to being screwed downwardly upon said neck so as to seal the bottle;

Fig. 2 is a side elevation, partly broken 50 away and partly in section, of the neck of the bottle, with the cap of our invention screwed downwardly thereon and sealing the mouth thereof, the cap being shown in section;

Fig. 3 is a central vertical section through 55 the barrel portion of the cap of our invention;

Fig. 4 is a vertical section through the top portion of the cap detached from the barrel portion thereof; 60

Fig. 5 is a top view of the cap;

Fig. 6 is a vertical section, partly broken away, of a modified form of the cap embracing certain features of our invention, and 65

Fig. 7 is a top view, partly broken away, of the same.

In the drawings, referring to Figs. 1 to 5 inclusive, 10 designates the neck portion of a bottle, 11 the screw thread of usual character formed directly upon said neck, 12 the contents of the bottle, and 13 the cap of our invention.

The cap 13 comprises a cylindrical or barrel portion 14 grooved in its lower walls, as 75 at 15, to engage the thread 11 formed on the neck of the bottle, the top 16 having a depending central portion 17 and a gasket 18 applied upon the exterior side of said portion 17. The top 16 is of disk outline and 80 extends outwardly above the upper edges of the mouth of the bottle and seats against said edges when the cap is in operative position. The top 16 is held by the barrel portion 14, which portion 14 is vertically slit 85 at a suitable number of points, say four, to form spring fingers 19, whose upper ends are bent inwardly and given a reverse curvature, as at 20, to engage the upper and lower edges of the peripheral portion of the top 90 16. The reverse curvature, at 20, of the upper ends of the fingers 19 form hooks to engage the top 16, and these hook portions 20 engage the top 16 firmly but with sufficient freedom to permit the barrel portion 14 to 95 be screwed downwardly upon the neck portion 10 without effecting the rotation of said top after the latter has partly entered the mouth of the bottle. The upper edges of the material of the barrel portion 14 are 100 bent inwardly and downwardly forming a beading 21 and then inwardly to form a flange 22 which is directly upon the upper flat portion of the top 16 and serves to force the depending portion of said top into the 105 mouth of the bottle when the barrel portion 14 is screwed downwardly to its operative position shown in Fig. 2. The material cut

away from the upper portion of the barrel 14 for the formation of the spring fingers 19 results in there being formed in the beading 21 a number of recesses 23 which may be utilized to receive a blade or tool for aiding in the application of the cap to and its removal from the neck of a bottle.

The depending portion 17 of the top 16 is cylindrical and receives the gasket 18 which we regard as of special utility and which extends from the lower surface of the top 16 downwardly to about the lower edge of the depending portion 17. The gasket 18 is a continuous ring or band of rubber or other suitable packing material and has an inner flat wall engaging the wall of the depending portion 17, a flat top edge to engage the under surface of the top 16, an upper outer flat surface and a lower inwardly and downwardly beveled surface 24. The upper inner edges of the lip of the bottle are convex, and initially the gasket 18 projects outwardly over the inner upper edges of said mouth so that upon the application of the cap to the bottle the gasket becomes strongly pressed against the depending portion 17 of the cap, as will be understood on reference to Figs. 1 and 2. The compression of the gasket by the application of the cap to the bottle results in the gasket sealing against the facing surfaces of the neck of the bottle and the depending portion 17, and in addition the upper edge of the gasket moves over upon the inner rounded edge of the lip at the mouth of the bottle and thereby extends its sealing zone.

In the assembling of the parts of the closure the gasket 18 is applied upon the depending portion 17 of the top member 16, and said top member is then forced upwardly into the barrel 14 until the peripheral edges of said top member become caught by the hooks 20 at the upper ends of the fingers 19, the upper horizontal portion of said top member then being in engagement with the horizontal flange 22 formed on the barrel 14. The cap or closure may then be applied to the bottle, the barrel 14 being screwed downwardly upon the bottle and forcing the descent of the top 16 and the entrance of the depending portion 17 and gasket 18 into the mouth of the bottle. The barrel 14 may rotate independently of the top 16, and hence said top with its gasket, when moving to sealing position, has a direct vertical movement. On removing the cap or closure from the bottle the barrel 14 will be screwed in reverse direction and the hooks 20 will then force the top 16 and gasket 18 upwardly from the mouth of the bottle. As hereinbefore mentioned a knife blade or other instrument may be applied across the bottom 21, within opposing recesses 23, and utilized in screwing the bar-

rel 14 downwardly or upwardly, as the case may be. In every instance the neck of the bottle must be proportionate with relation to the cap or closure so that when the cap is applied the gasket 18 may be enabled to create a proper seal.

In Fig. 6 we show a modification in the construction of the barrel portion of the cap, this modification omitting the beading 21 and recesses 23 of Fig. 1 and forming the spring fingers 19 from a barrel 14 having a closed top 30, all the other features of construction being the same as those illustrated in Fig. 1.

In both forms of the invention shown, the barrel portion of the cap has a substantial upper end to press the non-rotary top 16 downwardly into the mouth of the bottle, and in both forms of the invention shown the top 16 is of the same construction as presented in Fig. 4 and has a direct downward movement into the mouth of the bottle and a direct upward movement therefrom, the barrel 14 rotating around said top 16 and serving to either depress the same into the mouth of the bottle or lift said top therefrom.

The special form of gasket 18 shown as applied upon the depending portion 17 of the top 16 is of special importance in the effectual sealing of the bottle in that by reason of the tapered lower edge 24 of said gasket, a gasket of substantial thickness may be forced into the mouth of the bottle and effectually seal the same, as illustrated in Fig. 2, the tapered lower edge 24 of the gasket permitting the gasket to gain a proper entrance to the mouth of the bottle.

What we claim as our invention and desire to secure by Letters-Patent, is:

1. A receptacle and a closure therefor comprising a barrel or skirt portion having a top member and integral side fingers slit and bent inwardly and having a reverse bend at their upper ends forming recessed hooks, a top having a depending central part to enter the mouth of the receptacle and a lateral flange extending outwardly from the upper end of said depending portion and engaged at its edges by said hooks and at its upper surface by said top member, and a vertical gasket on said depending portion to seal against the same and the inner side walls about the mouth of the receptacle, said barrel or skirt portion and said top being in independent parts and said barrel portion being rotatable around said top.

2. A receptacle and a closure therefor comprising a barrel or skirt portion having a top member and integral side fingers slit and bent inwardly and having a reverse bend at their upper ends forming recessed hooks, a top having a depending central part to enter the mouth of the receptacle and a lateral flange extending outwardly from the

upper end of said depending portion and engaged at its edges by said hooks and at its upper surface by said top member, and a vertical gasket on said depending portion 5 to seal against the same and the inner side walls about the mouth of the receptacle, said barrel or skirt portion and said top being in independent parts and said barrel portion being rotatable around said top, and 10 said receptacle and closure having interengaging portions for securing the closure on the receptacle.

3. A receptacle and a closure therefor comprising a barrel or skirt portion having 15 a top member and integral side fingers slit and bent inwardly and having a reverse bend at their upper ends forming recessed hooks, a top having a depending central part to enter the mouth of the receptacle 20 and a lateral flange extending outwardly from the upper end of said depending portion and engaged at its edges by said hooks and at its upper surface by said top member, and a vertical gasket on said depending 25 portion to seal against the same and the inner side walls about the mouth of the receptacle, said gasket having a downwardly and inwardly tapered lower edge, a wall to engage said depending portion of said top, a 30 wall to engage the adjacent surfaces of the receptacle and an upper edge to engage the flange of said top, and said barrel or skirt portion and said top being in independent

parts and said barrel portion being rotatable around said top. 35

4. A receptacle and a closure therefor comprising a barrel or skirt portion having its upper edge bent inwardly and downwardly to form a raised bead, a top member extended inwardly from the lower inner 40 edge of said bead, side fingers slit and bent inwardly from the side of the barrel portion and said bead and having a reverse bend at their upper ends forming recessed hooks and recesses in said bead at the points where 45 the upper ends of said fingers were cut therefrom, a top having a depending central part to enter the mouth of the receptacle and a lateral flange extending outwardly from the upper end of said depending portion and 50 engaged at its edges by said hooks and at its upper surface by said top member, and a vertical gasket on said depending portion to seal against the same and the inner side walls about the mouth of the receptacle, said 55 barrel or skirt portion and said top being in independent parts and said barrel portion being rotatable around said top.

Signed at New York, in the county of New York and State of New York, this 29th 60 day of August, A. D. 1919.

ALFRED INGRAM.
HARRY INGRAM.
